UNITED STATES PATENT OFFICE.

CHARLES H. WILLIAMS, OF SPRINGFIELD, MISSOURI.

EMERGENCY SWITCH AND FROG.

SPECIFICATION forming part of Letters Patent No. 787,711, dated April 18, 1905.

Application filed January 20, 1905. Serial No. 241,959.

To all whom it may concern:

Be it known that I, CHARLES H. WILLIAMS, a citizen of the United States, residing at Springfield, in the county of Greene and State of Missouri, have invented new and useful Improvements in Emergency Switches and Frogs, of which the following is a specification.

My invention relates to improvements in emergency switches and frogs, the object of 10 which is to provide a cheap, simple, and durable device for quickly and easily forming a switch connection with the main-line track of a railroad without cutting or changing either the rails or the ties of the main track. 15 These objects I attain by means of the device illustrated in the accompanying drawings, forming a part of this specification, in which—

Figure 1 is a view in elevation of the device as applied to the railway-track and by dotted lines shows connection with a switch-stand. Fig. 2 is a detail view showing the lead-point connection. Fig. 3 is a top view of the same. Fig. 4 is a detail view showing 25 one of the connections forming part of the frog at the crossing of the main rail. Fig. 5 is a top view of the same. Fig. 6 is a detail view showing the wedge. Fig. 7 is a view of the clamp for securing the frog and lead-point 30 to the main line in connection with the wedge shown in Fig. 6.

Similar letters indicate corresponding parts in the several figures.

A and B are the ordinary rails on the main-line track of the railroad.

C and D are the switch-rails of the temporary track connecting with the main line.

E represents the lead-point connection with the main line, which consists of two parts E² 40 and E³, suitably hinged for permitting the part E² to swing out and in for making connection and disconnection with the main line. For this purpose said part E² has an enlarged and elevated part, which rests over and on the 45 main-track rail for lifting the wheels of an engine or a car, so that the flange will pass freely over the main line. For connecting or securing this part to the main rail any ordinary means may be used. I prefer using the 50 clamp F, which passes around the lower part

of the inside of the main T-rail and under the T-rail passes up to the outside to receive a wedge G on the outside of the connecting part. By means of this wedge or clamp the connection is made rigid, as shown in Fig. 1. 55 The connection and disconnection may be made by the ordinary switch stand and lever when the switch is intended for use by work-trains or when more than temporary use is desired; but for use in case of wrecks and 60 emergencies the clamp and wedge are preferred. The point E² is made with its upper part E⁴, as stated, to fit over and upon the track-rail of the main line, with a projection E⁵ below that fits in the outer groove of the 65 T-rail of the main track. By this means cars may easily pass over the main rail onto the side track or from the side track onto the main line. The connection E³ is provided with extensions E⁶ or with holes for fish-plates 70 for connecting with the side-track rail. I prefer the former.

The connection of the inner rail C of the switch-track is made across the inner rail B of the main track by means of two points H 75 and I, which are made similar to the point E, above described as making the lead-point, having one of these points on each side of the main inner-track rail and the points coming together in the center of the main rail. For 80 this purpose the points H and I have the extended points H² and I², which go over the main track, made with square ends to fit each other on top of the main rail, as shown. Clamps and wedges, the same as the ones described above for holding the lead-point, may 85 also be used for securing these points. They also have hinge-joints for letting them swing out and in to free the main track when desired, and these points may also be connected 90 with the attachments of a switch-stand, as shown in Fig. 1, when desired for more or less permanent use; but for emergency purposes the clamp and wedge is preferred. The extension of the inner rail C of the side track 95 may be provided with an ordinary split switch-point.

As thus constructed the connection and disconnection of the switch with the main track may be quickly and easily made without cut- 100

- ting the rails of the main track or disturbing its ties, as is the case with the frog and switch connections now in use. By this means the train entering the switch passes over the main inner-track rail B in going to and from the main track. This switch as thus constructed is interchangeable and may be used in connection with a straight track or a curved one in going either direction and on either side.
- 10 Having thus described my invention, what I claim as new, and desire to secure by Letters Patent of the United States, is—
- 15 1. A connection for a switch-track with the main line having a hinged point, one part of said point passes upon and over the main rail and another part of said point entering the

groove of the main rail combined with a clamp and a wedge for securing the same, substantially as shown and described.

2. A point for connecting a temporary track 20 with the main line consisting of a part to pass upon the top of the rail of the main track and a part to enter the groove of the main-track rail combined with a clamp and wedge to hold the same in position substantially as shown 25 and described.

In testimony whereof I affix my signature in the presence of two witnesses.

CHARLES H. WILLIAMS.
